UNITED STATES PATENT OFFICE.

ISIDOR FRENCH AND JAMES FRENCH, OF NEW YORK, N. Y.

NECKTIE.

SPECIFICATION forming part of Letters Patent No. 269,040, dated December 12, 1882.

Application filed September 9, 1882. (No model.)

To all whom it may concern:

Be it known that we, ISIDOR FRENCH and JAMES FRENCH, of the city, county, and State of New York, have invented a new and useful 5 Improvement in Band-Bow Neckties, of which the following is a full, clear, and exact description.

Reference is to be had to the accompanying drawings, forming part of this specification, in which similar letters of reference indicate corresponding parts in all the figures.

Figure 1 is a perspective view of our improvement. Fig. 2 is a plan view of a part of the same, partly in section, through the line x x , Fig. 1. Fig. 3 is a sectional side elevation of the same, taken through the line y y , Fig. 2.

The object of this invention is to facilitate the attachment of band-bow neckties to collar-buttons and promote security in such attachments.

The invention consists in a band-bow necktie constructed with a bow provided with a shield recessed and slotted to receive the collar-button, and having a band-holding pin attached to it, and the separate band provided with an eye-plate at one end to receive the collar-button, and at the other end with a scale of size-marks to facilitate the adjustment of the band to the size of the collar upon which it is to be worn, as will be hereinafter fully described.

A represents an ordinary bow.

B is the band, which is made separate from the bow A.

To the rear side of the bow A is secured a shield, C, which is made of metal or other suitable material, and is slightly arched to form space between it and the bow A for the head of the collar button or stud.

To one end of the shield C is attached a pin, D, to enter the band B and hold it from being drawn out of the bow A. In the other end of the shield C is formed a recess to serve as a guide in applying the shield to a collar-button, and in the bottom of the said recess is formed a slot to receive the neck or stem of the collar button or stud, the said recess and slot being made of such a depth that the button or stud will be about at the center of the shield C.

To one end of the band B is attached an eye-

plate, E, of metal or other suitable material, the aperture of which is made of such a size that the said eye can be readily passed over the head of the collar button or stud.

If desired, the eye-plate E may be omitted and a button-hole formed in the end of the band B, to receive the collar-button. To the inner side of the other end of the band B is attached a strap, F, of leather or other suitable material, upon which is formed a scale of division-marks representing the various sizes of collars and bearing numbers corresponding with the size-numbers of the said collars, or the scale can be formed directly upon the band B.

In using the improvement, the end of the band B bearing the scale F is passed through the bow A, beneath the shield C, and the pin D is inserted in the said band B at the point of the scale F corresponding with the size of the collar upon which the necktie is to be worn. The band B is then passed around the neck of the wearer. The eye-plate E is passed over the collar button, and the shield C is then passed over the said button, as shown in Figs. 75 2 and 3. With this construction, the necktie can be readily applied to the collar of the wearer and will be held securely in place.

Having thus described our invention, what we claim as new, and desire to secure by Letters Patent, is—

1. A band-bow necktie, constructed substantially as herein shown and described, and consisting of the bow provided with a recessed and slotted shield, having a band-fasteening pin attached to it, and the band provided with an eye-plate at one end and a scale of size-marks at the other, as set forth.

2. In a band-bow necktie, the separate band B, provided with a scale, F, of size-marks, substantially as herein shown and described, to facilitate the adjustment of the said band to the size of the collar upon which it is to be worn, as set forth.

ISIDOR FRENCH.
JAMES FRENCH.
